His Attorney

UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRACK CIRCUITS

Application filed June 4, 1930. Serial No. 459,224.

My invention relates to railway track circuits, and has for an object the provision of means for reducing the time required for the release of the track relay armature when a train enters the associated section.

5 I will describe one form of track circuit embodying my invention, and will then point out the novel features thereof in claims.

The accompanying drawing is a diagrammatic view showing one form of track circuit embodying my invention.

Referring to the drawing, the reference characters 1 and 1^a designate the track rails of a railway, which rails are divided by insulated joints 2 to provide a track section A—B.

20 The reference character R designates a track relay having an armature 5 pivotally mounted at 5^a and biased by gravity to its open position wherein a front contact 6 is open. The relay includes a main winding 3 for closing the armature 5, and an auxiliary winding 4 for assisting the force of gravity in opening the armature. The main winding 3 is connected across the rails of section A—B, a resistance 7 preferably being included in series with this winding. The auxiliary winding 4 is connected across the rails of section A—B in series with the usual source of 25 track circuit current C, which, as here shown, is a battery.

The main winding 3 preferably has a relatively high resistance and the auxiliary winding 4 preferably has a relatively low resistance. The parts are so proportioned that when the section A—B is unoccupied, the force acting on the armature 5 due to the main winding 3 is considerably greater than the sum of the force of gravity and the force 30 acting on the armature due to the auxiliary winding 4. Under this condition armature 5 is closed, so that the front contact 6 is closed. When a train enters the section A—B, however, the wheels and axles will form a low 35 resistance shunt across the main winding 3

and the resistance 7, so that the main winding 3 will be substantially deenergized, and the current flowing in the auxiliary winding 4 will be materially increased. The action of the winding 4 will assist the force of gravity in opening armature 5, with the result that this armature will open much more quickly than if the winding 4 were not provided.

50 The safety factor required for railway track circuits is not affected by a track circuit embodying my invention, because the breakage of any wire or the failure of the source of current C, will result in the opening of armature 5 due to the force of gravity.

55 Although I have herein shown and described only one form of track circuit embodying my invention, it is understood that various changes and modifications may be made therein within the scope of the appended claims without departing from the spirit and scope of my invention.

60 Having thus described my invention, what I claim is:

1. In combination, a single insulated track section, a relay having an armature biased by gravity to the open position and a main winding for closing said armature as well as an auxiliary winding for assisting the force of gravity in opening said armature, a connection across the rails of said section including said main winding, and a second connection across the rails of said section including said auxiliary winding and a source of current.

70 75 80 85 90 95 100
2. In combination, a single insulated track section, a relay having an armature biased by gravity to the open position and a main winding for closing said armature as well as an auxiliary winding for assisting the force of gravity in opening said armature, a connection across the rails of said section including said main winding, and a second connection across the rails of said section including said auxiliary windings and a source of current in series.

3. In combination, a single insulated track section, a relay having an armature biased by gravity to the open position and a main winding for closing said armature as well as 5 an auxiliary winding for assisting the force of gravity in opening said armature, a connection across the rails of said section including said main winding and a resistance in series, and a second connection across the 10 rails of said section including said auxiliary winding and a source of current in series.

In testimony whereof I affix my signature.
HERBERT L. BONE.
